(57) **CLAIM**

An ornamental design for a guitar body, as shown and described.

DESCRIPTION

FIG. 1 is a top front perspective view of a guitar body embodying my new design.

FIG. 2 is front elevation view of the guitar body of FIG. 1.

FIG. 3 is a rear elevation thereof.

FIG. 4 is a right elevation view thereof.

FIG. 5 is a left elevation view thereof.

FIG. 6 is a top view thereof; and,

FIG. 7 is a bottom view thereof.

Broken lines are used to illustrate features of the guitar body which form no part of the claimed design.
